UNITED STATES PATENT OFFICE.

HENRY P. HUNTER, OF ANDERSON, SOUTH CAROLINA.

WARP STOP MOTION.

Application filed October 29, 1926. Serial No. 145,045.

This invention is a novel improvement in warp stop motions for looms, and the principal object of the invention is to provide a simple, novel, and efficient warp stop motion, constructed so as to insure quick acting and positive stopping of the loom in case one or more warp threads should break, the heddles in no way confining or weighting the warp threads.

Another object of the invention is to provide a novel pivoted detector, or heddle, which will not weight or confine the warp threads, but will allow the threads to pass from the whip-roll through large slots in the upper lighter ends of the heddles to the harness, whereby no tension will be exerted on the threads, such as is the case when using the ordinary or usual "drop wires" suspended from the warp threads. In my invention no lease rods, or rods of any kind, are necessary to hold the yarn down in order to facilitate the action of the heddles, thereby permitting the yarn in the upper harness to remain slack, and allowing the filling threads to be easily driven into place, preventing the production of "reedy cloth" by the loom. Other minor objects of the invention will be hereinafter set forth.

I will explain the invention with reference to the accompanying drawings which illustrate one practical embodiment thereof, to enable others familiar with the art to adopt and use the same, and will summarize in the claims the novel features of construction, and novel combinations of parts, for which protection is desired.

In said drawings:—

Fig. 1 is a perspective view of my novel warp stop action applied to a loom;

Fig. 2 is an enlarged end view of the stop motion detached showing the banks of heddles in position to permit operation of the loom;

Fig. 3 is a partial end elevation of the warp stop motion;

Fig. 4 is a section through the stop motion on the line 4—4, Fig. 3, showing the banks of heddles in position to prevent operation of the loom.

As shown in the drawing, my stop motion preferably is housed in a frame consisting of side members 1^a, and end members 1^b, said side members being of sufficient length to extend across the full width of the loom, in rear of the harness, and over and slightly in front of, the warp beam. The frame is pref-

erably open at its top and bottom, and is provided with pairs of projecting lugs 1^c from each end 1^b, said lugs being adapted to rest upon tables A' on the loom frame 60 to support the frame in operative position on the loom, bolts A² in tables A' being disposed between the lugs 1^c to position the frame on the tables. Within the frame are two spaced parallel rods 4 and 5, adjacent 65 the upper end of the frame, for pivotally supporting the banks of heddles, designated by the numerals 2 and 3 in the drawings, the rods 4 and 5 being threaded at each end and provided with nuts for maintaining the rods 70 in the frame.

Heddles 2 and 3 are formed substantially L-shaped, the vertical legs 2^a, 3^a being preferably oval-shaped, and provided with large, oval-shaped openings. The horizontal legs 75 of the heddles are provided with hooks 2^c, 3^c, at their lower ends for the purpose herein-after set forth. The heddles are pivoted on the parallel rods 4 and 5 within the frame, the pivots for the heddles being disposed at 80 points nearer the oval-shaped vertical ends 2^a, 3^a than the hooked ends 2^c, 3^c causing the preponderance of weight of the heddles to be at the hooked ends 2^c, 3^c, so that the hooked ends will normally drop by gravity. 85 The heddles are arranged on the rods 4, 5, with the vertical legs of one bank of heddles disposed toward the back of the loom, and vertical legs of the other bank of heddles disposed toward the harness or front end 90 of the loom.

The warp threads L are passed through the openings in the vertical legs of the heddles so that the threads will touch the lower ends of the openings to maintain the hooked ends 2^c, 3^c of the heddles in raised position, but if any thread should break, its related heddle would immediately drop and thereby cause the loom to stop as hereinafter described. Each heddle 2 and 3 will have as 100 many warp threads passing through the slot in its vertical leg as there are harnesses required to weave the particular fabric being woven. Hence, if print-cloth sheeting, or other cloths which are ordinarily woven with two harnesses are being made, it is necessary to pass two threads through the slot or opening in each heddle, in order that one warp thread will always be down when the loom picks, and never more than one thread. 105 The heddles 2 and 3 are held down by the lower thread so that, if a thread from either

the front or back harness breaks, the loom will stop when that harness is depressed.

In weaving a drill, or three-harness weave, three threads can be drawn per heddle, if the harnesses are set for a two up and one down weave. For a four-harness twill, woven three up and one down, four threads per heddle can be carried by the heddles, and for a five-harness (sateen) weave, five threads can and must be drawn per heddle. It can be seen that this arrangement will greatly reduce the necessary number of heddles, it being customary to use one heddle for each thread contained in the warp.

15 Below the heddles 2 and 3, in the frame, are parallel rock shafts 8 and 9 journaled in the end members 1^b of the frame adjacent the bottom thereof, and on shafts 8 and 9 are intermeshing quadrants or gears 10 and 20 11 respectively where the motion of one shaft is imparted to the other to cause the other to rock in the opposite direction. On shafts 8 and 9 respectively are upright arms 8^a, 9^a respectively carrying plates 6 and 7, which are adapted to oscillate immediately below hooked ends 2^c, 3^c, of the heddles when the heddles are maintained in raised position by the warp threads, but in case a heddle should drop due to the breaking of a warp 30 thread the plate 6 or 7 would engage the hooked end of the heddle and prevent the oscillation of plates 6 and 7 as shown in Fig. 4.

Hence the motion of rock shafts 8 and 9 causes the plates 6 and 7 to oscillate so that their inner edges almost touch each other when they are oscillated toward the center of the box as shown in Fig. 4, and to nearly touch the sides of the box when they are oscillated in the outward direction as in Fig. 2. A positive movement is provided for moving the plates 6, 7, toward each other, but the outward return movement is caused by a yieldable spring hereinafter described 45 having one end attached to the loom frame and the other end attached to a lever keyed to one of the shafts 8 or 9, whereby the motion can be easily stopped, if one of the heddles should be released by the breaking of a warp thread, at which time the heddle would drop into a position that the hook 2^c or 3^c would engage the plate 6 or 7.

The means for positively moving the plates toward each other comprises an arm 9^b loosely mounted on the shaft 9 and readily rotatable thereon. Arm 9^b is held in place on said shaft by collars 9^c, 9^d, fixedly mounted on the shaft 9 at each side of the arm 9^b to prevent end-wise movement. On 55 the inner side of one collar 9^d is a projection 9^e adapted to enter an arcuate slot 9^f in the adjacent face of the hub of arm 9^b. The collars are attached to the shaft 9 by means of set screws, and the two projections 9^e adjusted to proper position in the slot 9^f before

the collar 9^d is fastened to the shaft 9 by its set screw above mentioned. The projection 9^e and slot 9^f allows the arm 9^b to rock the shaft 9 in one direction only; that is, when the arm 9^b is rocked in a direction which causes the slot in its hub to press against the projection 9^e on the rigidly attached collar, the shaft 9 is revolved in that direction, and by reason of gears 10 and 11 plates 6 and 7 are moved towards each other. Attached to the rock shaft 9 is another arm 9^h which extends horizontally, toward the back of the loom, and lever 9^h is connected with one end of a spring 12, the other end of spring 12 being attached to a stud A³ on the frame of 80 the loom. The rock shaft 9 to which the arm 9^h is attached, extends through the end 1^b of the heddle frame a sufficient distance to receive the arm 9^h whereby the arm 9^h is disposed outside the heddle box and near the 85 side of the loom.

On the crank shaft A⁴ of the loom, is an eccentric 13, preferably made in two parts in order that it may be easily placed on the crank shaft, and to eccentric 13 is attached 90 a connecting rod 13^a by means of an eccentric strap, 13^b. The outer end of the rod 13^a is attached to the arm 9^b and imparts to it a rocking motion as the crank shaft A⁴ rotates. One motion of arm 9^b causes the two 95 plates 6, 7, to move toward the center of the heddle box or toward each other. The return motion of the arm would leave the plates 6, 7, in this central position by reason of the pin and slot engagement of arm 9^b and collar 9^d, but the movement of the shaft 9 to carry the plates 6, 7, to their central position has raised the spring arm 9^h thereby increasing the tension of the spiral spring 12, which causes the shaft 9 to return with 100 the arm 9^b unless its movement is arrested by the dropping of the hook on one of the heddles 2, 3, caused by the breaking of a 105 thread L.

Attached to the rock shaft 9 but at the 110 opposite end to that to which the lever 9^h is attached, is an arm 23 which is connected through a link 14 with the usual means for stopping the operation of the loom.

The heddles, as arranged in my warp stop 115 motion, do not in any way detract from the appearance of the cloth, but permit the weaving of a fabric as free from a "reedy" appearance as could be woven were no warp stop motion used on the loom.

I do not limit my invention to the exact form shown in the drawings for obviously changes may be made therein within the scope of the claims.

I claim:

1. In a warp stop motion for looms, a frame; a rod in said frame; a plurality of heddles for the warp threads pivotally mounted on said rod, said heddles having hooked lower ends; and oscillating member 130

mounted in the frame below the hooked ends of said heddles and adapted to control the operation of the loom and means for positively moving the member in one direction; and means for yieldably moving the member in the opposite direction, each heddle comprising a substantially L-shaped member having a slot for the warp threads in its vertical leg; the hook being on the horizontal leg; and the pivot point being disposed nearer the slotted end than the hooked end, whereby the hooked end thereof will normally drop by gravity into the path of related oscillating member.

2. In a warp stop motion for looms, a frame; a rod in said frame; a plurality of heddles for the warp threads pivotally mounted on said rod, said heddles having hooked lower ends; and oscillating member mounted in the frame below the hooked ends of said heddles and adapted to control the operation of the loom and means for positively moving the member in one direction; and means for yieldably moving the member in the opposite direction, said positive moving means comprising a lateral projection on said oscillating member; a lever loosely mounted on said member and having an arcuate slot therein for said projection; an eccentric on the loom shaft; and a link connecting the eccentric with the lever.

3. A warp stop motion comprising a frame adapted to be mounted on a loom; parallel rods mounted in said frame; opposed banks of heddles pivotally mounted on said rods, said heddles having depending hooks on their lower ends, the lower hooked ends of one bank crossing those of the other bank; positively moving oscillating members mounted in the frame below each bank of heddles and adapted to be embraced between the hooked ends of the bank in one position of the heddles to prevent separation of the members; means for positively moving the members towards each other; means for yieldably separating the members; and a control connected with said members for stopping the operation of the loom when the hooked end of one or more heddles engage its related oscillating member.

4. In mechanism as set forth in claim 3, each heddle comprising a substantially L-shaped member having a slot for the warp threads in its vertical leg, the hook being on the horizontal leg; and the pivot point being disposed nearer the slotted end than the hooked end, whereby the hooked end thereof will normally drop by gravity into the path of related oscillating member.

5. In mechanism as set forth in claim 3, said positive moving means comprising a lateral projection on said oscillating member; a lever loosely mounted on said member and having an arcuate slot therein for said projection; an eccentric on the loom shaft;

and a link connecting the eccentric on the loom shaft; and a link connecting the eccentric with the lever.

6. A warp stop motion comprising a frame adapted to be mounted on a loom; parallel rods mounted in said frame; opposed banks of heddles pivotally mounted on said rods, said heddles having depending hooks on their lower ends, the lower hooked ends of one bank crossing those of the other bank; parallel rock shafts mounted in the frame below said rods; oppositely moving oscillatory members on said rock shafts below the hooked ends of said heddles and adapted in one position of the heddles to be embraced between the hooked ends to prevent separation of the members; means for positively moving the members towards each other; means for yieldably separating the members; and means connected with said rock shafts for stopping the operation of the loom when the hooked end of one or more heddles engage its related oscillating member.

7. In mechanism as set forth in claim 6, each heddle comprising a substantially L-shaped member having a slot for the warp threads in its vertical leg; the hook being on the horizontal leg; and the pivot point being disposed nearer the slotted end than the hooked end, whereby the hooked end thereof will normally drop by gravity into the path of related oscillating member when the warp thread is broken.

8. In mechanism as set forth in claim 6, said rock shafts being geared together; and said positive moving means comprising a collar on one rock shaft having a lateral projection; a lever loosely mounted on said rock shaft adjacent the collar and having an arcuate slot therein for said projection; an eccentric on the loom shaft; and a link connecting the eccentric with the lever.

9. A warp stop motion comprising a frame adapted to be mounted on a loom; parallel rods mounted in said frame; opposed banks of heddles pivotally mounted on said rods; the hooks of one bank crossing and opposing those of the other bank; said heddles having depending hooks on their lower ends; parallel rock shafts mounted in the frame below said rods; intermeshing gears on said rock shafts; oppositely moving oscillatory members on the rock shafts respectively below the hooked ends of said heddles and adapted in one position of the heddles to be embraced between the opposed hooked ends to prevent separation of the members; means for positively driving the members towards each other; means for yieldably separating the members; and means connected with said rock shafts for stopping the operation of the loom when the hooked end of one or more heddles engage its related oscillatory member.

10. In mechanism as set forth in claim 9, each heddle comprising a substantially L-shaped member having a slot for the warp threads in its vertical leg; the hook being 5 on the horizontal leg; and the pivot point being disposed nearer the slotted end than the hooked end, whereby the hooked end thereof will normally drop by gravity into the path of related oscillating member, when 10 the warp thread is broken.

11. In mechanism as set forth in claim 9, said positive driving means comprising a collar on one rock shaft having a lateral 15 projection; a lever loosely mounted on said rock shaft adjacent the collar and having an arcuate slot therein for said projection; an eccentric on the loom shaft; and a link connecting the eccentric with the lever.

12. In mechanism as set forth in claim 9, 20 said yieldable means comprising a lever on one rock shaft; and a spring connecting said lever with the loom frame.

13. A warp stop motion comprising a frame adapted to be mounted on a loom; 25 parallel rods mounted in said frame; opposed banks of heddles pivotally mounted on said rods, each heddle comprising a substantially L-shaped member having a slot for the warp threads in its vertical leg; and 30 having a depending hook on the outer end

of its horizontal leg; the warp threads engaging the lower end of the slots; and the pivot point being disposed nearer the slotted end than the hooked end, whereby the hooked end thereof will normally drop by gravity 35 when the thread is broken; oscillating members mounted in the frame below said heddle banks; means for positively driving the members towards each other; means for yieldably separating the members; and 40 means connected with said members for stopping the operation of the loom when the hooked end of one or more heddles engage its related oscillating member.

14. In mechanism as set forth in claim 13, 45 said positive driving means comprising a lateral projection on said oscillating member; a lever loosely mounted on said member and having an arcuate slot therein for said projection; an eccentric on the loom 50 shaft; and a link connecting the eccentric with the lever.

15. In mechanism as set forth in claim 9, 55 said yieldable means comprising a lever on said oscillating member, and a spring connecting said lever with the loom frame.

In testimony that I claim the foregoing as my own, I affix my signature.

HENRY P. HUNTER.
